UNITED STATES PATENT OFFICE.

WILLIAM H. ROBERTSON, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed June 7, 1923. Serial No. 643,920.

This invention relates to cash registers, and particularly to improvements in the type of machine shown in the Von Pein application for Letters Patent of the United States, Serial No. 460,882, filed April 13, 1921.

An object of this invention is the provision of an improved indicating mechanism for displaying the items both in the front and rear of the machine.

Another object of this invention is the provision of an improved mechanism for obscuring the indicators from view during the operation of the machine.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1^A and 1^B taken together constitute a rear elevation of the machine.

Fig. 2 is a detail view of a part of the indicator mechanism.

Fig. 3 is a detail view of the indicator elevating cam.

Fig. 4 is a transverse sectional view of the machine, taken to the right of the totalizer.

Fig. 5 is a detail side elevation of the mechanism for operating the common driving shaft.

Fig. 6 is a side elevation of the mechanism between the printer plate and the side frame of the machine.

Fig. 7 is a detail rear elevation of a portion of the indicator selecting mechanism.

Fig. 8 is a detail view of the indicator aliner cam.

Fig. 9 is a side elevation of the printing mechanism.

The embodiment illustrated comprises the usual amount keys, means for entering amounts in a totalizer and for printing the same. In addition, mechanism is provided for indicating the amounts. An obscuring device covers the indication while the machine is being operated.

Referring especially to Fig. 4, the invention is shown in connection with the well known lever key type machine. The keys

25, arranged in denominational groups as usual, are pivoted on a transverse rod 26 carried by the side frames of the machine, and at their rear ends are notched to cooperate with a lip on a key coupler 27 and 60 rock it a sufficient distance to permit an arm 28, pivoted on a stud 29, to swing forward under the lip of the key coupler, in which position the key coupler is retained until after the printing operation has been completed. The key coupler is provided with 65 trunnions 30 having bearings in the side frames 31.

The rear ends of the keys are extended to cooperate with pivoted key stops 32 which 70 prevent a simultaneous depression of a plurality of keys in single denominational groups.

Uprights 33, connected to the rear ends of the keys, are provided with notches 34 for 75 engaging rods 35 carried by a rocker member 36, supported on a shaft 37. There is a rocker member for each denominational group of keys 25, and each of the members is operatively connected to its registering segment or totalizer actuator 38. The notches in the uprights 33 are located to transmit amounts of movement to the actuators proportionate to the number of units represented by the keys to which the uprights are 80 connected.

The totalizer actuators are normally in mesh with gears 39 connected to the item type wheels 40 (Fig. 9) by telescopic sleeves 41, (Fig. 4) to print the items on an issuing receipt which will hereinafter be described.

The key coupler 27, before referred to, is pivotally mounted in the side frames and rests upon the rear ends of the keys from 85 which it receives its movement. The right hand end of the key coupler carries a roller 45 (Fig. 5) which cooperates with a slot in a driving member 46 guided on a stud 47 projecting from the frame of the machine. The driving member is provided with opposing racks adapted to be thrown into mesh alternately with a gear 48 on a cam shaft 49 to move the shaft in a counter-clockwise direction. The engagement of 100 the racks with the gear is controlled by a spring 50, a spring-drawn arm 51, a flange 52 on the rack, and a flange 53 on the frame, operating in the usual manner.

A notched disk 54 cooperates with a 110

spring-actuated pawl 55 to prevent a retrograde motion of the shaft 49 after it has been moved a certain distance.

Secured to the cam shaft 49 is a cam 56 which engages two rollers 57 carried on a lever 58 which is operatively connected to a totalizer 59 to rock the totalizer on its pivot 60 and engage gears 61 with the actuators 38 to enter the items registered by the item 10 entering keys 25. This totalizer being of such a well known type, a detailed description of the mechanism will not be given here.

The cam shaft 49 (Fig. 6) extends 15 through the right hand side frame and has secured thereto a disk 65. The initial or downward movement of the item key 25, which has previously been described, will rotate the disk 65 one hundred and eighty 20 degrees in a counter-clockwise direction. Formed in the disk is a cam groove 66 and a stop shoulder 67 which cooperates with a roller 68 mounted on the upper end of an arm 69 freely mounted on a rod 70 supported in the frame of the machine. A projection 71 on the arm 69 engages with a roller 72 mounted on a lever 73 pinned to a rockable rod 74. A tension spring 75 attached to the lever and to the side frame 25 holds the roller 72 in engagement with the end of the projection 71. As the shaft 49 revolves 180° the arm 69 moves clockwise, raising the end of the projection 71 above the roller 72, allowing the spring 75 to move 30 the lever 73 clockwise into engagement with the key coupler trunnion 30 and disengaging a hook-shaped end 76 on the lever 73 from a square pin 77 mounted in a disk 78 secured to a driving shaft 79.

40 Pinned to the rod 74 (Fig. 4) is an arm 80 carrying a pin 81 which engages a bifurcated end of an arm 82 integral with the arm 28 to prevent the hook 76 (Fig. 6) from disengaging from the pin 77 until the arm 28 (Fig. 4) is moved under the key coupler 27 a sufficient distance to arrest the key coupler until released by mechanism hereinafter described.

In addition to the driving shaft locking 50 means previously described, there is a second locking means which is released by rotation of the shaft 49 through 180° . Pivoted on the rod 70 (Fig. 6) and secured to the arm 69 by a stud 84 is a three-armed lever 85, with 55 its forwardly extending arm 86 carrying a pin 87 normally engaging a notch 88 formed in a pivoted member 89 supported by a rod 90 secured in the frame of the machine. The arm is held in engagement with the pin 87 by a spring 91 with one end attached to the arm 89 and the other attached to the arm 86. As the shaft 49 revolves, the arm 86 moves clockwise and moves the pin 87 from the notch 88 into a notch 92, where it will be 60 retained until returned to its normal posi-

tion near the end of the printing operation. With the pin 87 in the notch 92 the roller 68 is in engagement with stop shoulder 67. A rearwardly extending arm 93 has a hook 94 formed at its end to engage a plate 95 secured to a cam 96 which forms a means of stopping the driving shaft 79 at the end of its operation and locking the same against operation until an item key 25 has been depressed, as previously described. 75

After the printing operation is completed, the key coupler is permitted to return to its normal position, together with the item keys that were depressed. The mechanism for releasing the key coupler comprises a disk 100 (Fig. 6) fast to the drive shaft 79, and provided with a projection 101 adapted to engage a downwardly extending arm 99 of the lever 85. As the disk 100 is nearing the completion of its rotation in a counter-clockwise direction, the projection 101 will cause the arm 69 to move in a counter-clockwise direction, placing the roller 68 in the groove 66, and through the shaft 74 and arm 80 (Fig. 4) moving the supporting arm 28 in a clockwise direction, thereby permitting the key coupler and keys to return to normal position and to rotate the shaft 49 to operate the transfer mechanism. 85

The driving shaft 79 may be operated by 90 any suitable power means as well as a manually operated means, as shown in Fig. 9. Fast to the driving shaft is a gear 102 in mesh with a pinion 103 freely mounted upon a stud 104 (Figs. 1^A and 9) and connected 100 to an operating crank 105 by a standard clutch mechanism, well known in the art, but not shown here. As the pinion is only half the size of the gear the operating crank will 105 make two revolutions during each operation of the machine.

A cam groove 106 (Fig. 9) formed in the side of the gear 102 cooperates with a roller 107 carried on an arm 108 freely mounted at one end on a stud 109 supported by a 110 printer frame 110. The forward end of the arm is freely connected by a screw stud 111 to a platen bearing member 112 having a downward projection bifurcated so that it will be guided by the operating crank stud 115 104. The platen bearing member moves upward during each operation of the machine to take impressions from the item type wheels 40, the date and consecutive number wheels 113, and suitable electroplates, (not shown) upon a strip 114 which is fed from a supply roll 115. The strip is fed at each operation of the machine by feed rollers 116 and 117 (Fig. 9) which are actuated by a segment arm 118 (Fig. 6) freely mounted 115 upon a rod 119 and having downwardly extending arms carrying rollers 120 and 121 cooperating respectively with cams 96 and 122 secured to the driving shaft 79. This segment arm engages a gear and ratchet 125 130

feeding device 123 which is operatively connected to the feed rollers, all of which is well known in the art.

The segment arm 118 has an upwardly extending arm 124 having a cam slot 125 cooperating with a roller 126 to actuate the consecutive number type printing wheels 113 (Fig. 9). Another arm 127, also a part of the segment arm 118, actuates a type printer wheel alining arm which is not shown here. Several parts of the printing mechanism are not shown for the reason that they play no important part in this invention, and as they are fully illustrated and described in the Von Pein application previously referred to.

The registering segment 38 (Figs. 4 and 7) in addition to actuating the totalizer and type printing wheel, actuates a target indicator selecting device. Each registering segment 38 is in constant engagement with a pinion 135. These pinions are connected to a companion pinion 136 by hubs 137 freely mounted upon a rod 138 supported by the frames of the machine. The companion pinions 136 mesh with segments 139 which are secured to segments 140 in mesh with gear racks 141. The segments are secured to hubs freely mounted upon a rod 142 and laterally spaced by collars 143.

The gear racks 141 are supported at their forward ends by the rod 138 and their rear ends are pivoted on a stud 144 secured in indicator selecting arms 145 which are freely mounted on a rod 146 and telescopic sleeves 162 surrounding this rod later described. The indicator selecting arms are moved to positions corresponding to the item keys depressed in their respective groups.

After the indicator selecting arms 145 are adjusted, they are held stationary by an alining device until the indicator supporting members are moved to a corresponding position. Formed in the upper part of the selecting arms 145 are notches 147 corresponding in number to the indicator tablets in a group. Cooperating with these notches is an alining arm 148 pinned to a rod 149 supported in the frame of the machine. Also pinned to the rod 149 is a downwardly extending arm 150 (Fig. 6) which is maintained in engagement with the upper end of a lever 151 by a spring 152. The lever is fulcrumed on a pin 153 supported in the frame of the machine and the lower end of the lever carries a roller 154 (Fig. 8) engaging a cam race 155 formed in the side of a gear 156 secured to the driving shaft 79. As the lever 151 is rocked counter-clockwise by the cam it will cause the alining arm 148 (Fig. 4) to enter a notch 147.

Cooperating with each indicator selecting arm 145 is an indicator supporting frame 65 consisting of two upright members 160

(Figs. 1^A and 2) secured at their lower ends on hubs 161. The left hand hub in Fig. 1^A is pinned to the rod 146. The next hub to the right is secured to a sleeve 162 which is freely mounted on the rod 146, and the third or right hand hub is freely mounted on the sleeve of the second hub. The upper ends of the upright members are joined by a yoke 163 which also supports the indicator tablets 164 in their normal position. The upper ends of the members 160 are offset slightly and are provided with radial slots 165 uniformly spaced and adapted to receive the indicator tablets.

The indicator supporting members are moved into a position corresponding to the actuated position of the indicator selecting arms 145 by pairs of arms 166 joined together at their upper ends by pins 167 upon which are freely mounted rollers 168 engaging the sides of openings 169 in the members 160. Similar openings 170 in the indicator selecting arms 145 form means for guiding the indicator supporting members to position as the rollers 168 move to the upper part of the openings.

The arms 166 are secured on opposite ends of sleeves 159 which are freely mounted upon a rod 177 supported at each end by arms 178 which are pinned to a rod 179 supported by the frame of the machine.

During the operation of the machine the rod 179 is rocked by an arm 171 (Fig. 2) pinned to the rod 179 at one end and a pitman 172 pivoted on the other end carrying a roller 173 engaging a cam race 174 formed in the side of a gear 175 which is secured to a shaft 176. The gear 175 is in mesh with the gear 156 and makes one revolution at each operation of the machine.

After the indicator supporting members are moved into adjusted position, the indicator tablets which correspond to the item keys depressed are raised into displaying position. The means for accomplishing this consists of a horizontal bar 180 (Figs. 1^B and 4) extending across the top of the machine and secured to vertical plates 181 at each end. These plates are guided in their operations by brackets 182 secured to side frames of the machine. Each bracket is provided with vertical openings 183 in which move rollers 184 and studs 185 mounted on the plates 181.

The horizontal bar 180 and plates 181 are given a reciprocal motion by links 186 connecting the studs 185 with arms 187 which are integral with partial gears 188 freely mounted on studs 189 (Fig. 6) supported in the frames of the machine. These partial gears mesh with segment gears 190 which are pinned on a rod 191 supported in the frames of the machine.

The rod 191 is oscillated by a link 192 connecting the segment gear 190 with an 130

arm 193 freely mounted on the rod 179. This arm is rocked by a pitman 194 carrying a roller 195 engaging a cam 196 secured to the shaft 176 (Fig. 3). The cam is formed so as to move the horizontal bar 180 downward to place the last indicators displayed in their normal position before the indicator supporting members are moved to the new positions, corresponding to the last 16 item keys depressed. After the indicator supporting members assume their new positions the horizontal bar is returned to its upward or normal position, displaying the new indication.

15 The lower edge of the horizontal bar 180 (Figs. 1^a and 4) has a plurality of slotted openings 200 through which the tops 201 of the indicator tablets 164 pass when rocked by the supporting members. Notches 202 formed on opposite sides of the indicator tablets engage horizontal lugs 203 on the bar 180 to support the indicator tablets in their display position.

16 The indicators are arranged to be displayed in two groups, one group to be seen from the front of the machine and the other from the rear. The group of indicators shown to the right in Fig. 1^a, being the center group, are arranged with characters 25 on both sides of the tablets and indicate to both front and rear. The other groups of indicators in Fig. 1^b are seen only from the rear of the machine, and their supporting members 204 are moved in unison with their respective supporting members in Fig. 1^a by the connection afforded by the rod 146 and telescopic sleeve 162 secured to the hubs of the members 160.

17 The indicators are displayed through 40 openings in plates 205 supported by the brackets 182. Upon the operation of an item key 25 the indicators displayed by the last printing operation will be obscured by horizontally moving plates 206 which are pivotally supported on swinging yokes 207 placed at each side of the machine. These yokes are freely mounted on studs 208 secured in the plates 205. The obscuring plates are moved by means of a bifurcated arm 209 (Fig. 1^a), 45 being integral with the yoke 207, and engaging a pin 210, secured in the upper end of a vertically moving plate 211, which is supported on and guided by studs 212 and 213 (Fig. 6) mounted in the side frame of the machine and in engagement with openings 214 and 215 respectively.

18 The lower end of the plate 211 is formed with a horizontal projection 216 (Figs. 5 and 6) offset to extend inside the frame and 50 bifurcated to engage the key coupler 27 to raise the plate 211 and move the obscuring plates 206 laterally and close the openings through which the indicators are seen. As the key coupler returns to normal position 55 the obscuring plates will also return to their

normal position and permit the new indication to be seen.

Operation.

An amount is registered, printed and indicated on this machine as follows:

19 Keys corresponding to the amount involved are depressed as usual in this type of machine. This operation causes the amount to be added on the totalizer and set up on 75 the type wheels as usual. In addition this operation of the keys also moves the indicator selecting arms 145 into positions corresponding to the keys depressed.

20 The movement of the keys raises the key 80 coupler 27 (Fig. 4) permitting the retaining means 28 to move under the key coupler until an operation of the printing mechanism has taken place, the printing mechanism being released by the cam 65 shown in 85 Fig. 6 just as the keys reach their lowermost position. The indicator tablets previously selected and exposed to view are obscured by the plates 206 (Figs. 1^a and 1^b) which are 90 operated from the key coupler through the plate 211 (Fig. 6).

21 The printing is performed by operating the mechanism shown in Fig. 9 from the crank handle 105. This lowers the indicator lifting bar 180 at the beginning of the movement of the crank handle by means of the links 186, etc. shown in Fig. 6, operated by the cam shown in Fig. 3. The indicator selecting arms 145 previously adjusted by the keys are now aligned by the aliner 148 100 (Fig. 4) operated by the mechanism shown at 150, 151, etc. in Fig. 6. Further movement of the crank handle raises the driving pins 167 (Fig. 2) to adjust the indicator supporting frame 160 as determined by the 105 position of the indicator selecting arms 145 (Fig. 4). The indicator tablet which has been positioned below the space between the plates 205 (Fig. 4) is now lifted by the lifter bar 180 in position to be exposed 110 through openings in said plates.

22 An impression has been taken on the receipt strip 114 by the mechanism shown in Fig. 9. The crank handle is now brought to its home position. This releases the key 115 coupler by restoring the interlocking parts shown in Fig. 6 to normal. The key coupler now returns to normal, permitting the plate 211 to lower to move the obscuring plates 206 to the right (Fig. 1^a) to expose the 120 raised indicator tablets to view.

23 The parts are now in home position ready to be operated to register, print and indicate another transaction.

24 While the form of mechanism herein 125 shown and described is admirably adapted to fulfill the objects primarily stated, it is to be understood that it is not intended to confine the invention to the one form of embodiment herein disclosed, for it is sus- 130

ceptible of embodiment in various forms all coming within the scope of the claims which follow.

What is claimed is:

5. 1. The combination of a movable tablet indicator supporting carriage, differentially movable means for controlling the movement of said carriage, manipulative means for controlling said differentially movable means, an operating means, means for normally locking said operating means, means for moving said locking means for releasing said operating means after the adjustment of said differentially movable means has been effected, and means operated by said operating means for moving said carriage under control of said differentially movable means.

2. In a machine of the class described, the combination of a totalizer, a totalizer actuating means, item entering means adapted to operate said actuating means, an oscillating member actuated by said actuating means, indicating elements, indicating elements adjustable supporting means, means cooperating with said oscillating member and said indicating elements supporting means for adjusting said supporting means, and an operating means independent of said item entering means for actuating said adjusting means.

3. In a machine of the class described, the combination of a totalizer, a totalizer actuating means, an item entering means for operating said actuating means, an operating device operable only after a partial operation of the item entering means, indicating elements, a movable means supporting said indicating elements, a second movable means operated by said actuating means, and means operated by said operating device for moving said indicating elements supporting means to a position corresponding to that of said second movable means.

4. In a machine of the class described, the combination of item entering means, an actuating means, means intermediate the item entering means and the actuating means for differentially moving said actuating means, an operating device operable only after a partial operation of the item entering means, indicating elements, a movable means supporting said indicating elements, a second movable means operated by said actuating means, means operated by said operating device and cooperating with said second movable means for moving said indicating elements supporting means to a position corresponding to that of said second movable means, and means for locking said second movable member in position while said first movable member is being moved into position.

5. In a machine of the class described, the combination of item entering means, an act-

uating segment differentially moved by said item entering means, an operating device operable after a partial operation of the item entering means, indicating elements supported by a movable member, a second movable member adapted to be moved differentially by said actuating segment, a rack pivoted to said second movable member, gears intermediate said rack and said actuating segment adapted to transmit motion from said actuating segment to said rack, and means operated by said operating device and cooperating with said second movable member to differentially position said indicating elements supporting member.

6. In a machine of the class described, the combination of a totalizer, a totalizer actuating means, an item entering means for operating said actuating means, an operating device operable only after a partial operation of the item entering means, indicating elements, a movable means supporting said indicating elements, a second movable means operated by said actuating means, means operated by said operating device for moving said indicating elements supporting means to a position corresponding to that of said second movable means, and means operated by said operating device for elevating one of said indicating elements to a display position.

7. In a machine of the class described, the combination of item entering means, an actuating means, means intermediate the item entering means and the actuating means for differentially moving said actuating means, an operating device operable after a partial operation of said item entering means, indicating elements, a pivoted member supporting said indicating elements, a second pivoted member operated by said actuating means, means operated by said operating device and cooperating with said second pivoted member for adjusting said first pivoted member, means for locking said second pivoted member, and means operated by said operating device for moving one of said indicating elements into indicating position.

8. In a machine of the class described, the combination of a totalizer, a totalizer actuator, item entering means, an operating device operable only after a partial operation of the item entering means, a plurality of indicators, a movable indicator supporting means adapted to be moved into adjusted position by said operating means under control of said totalizer actuator, means operated by said operating device for raising one of said indicators to a displaying position, and means operated by said item entering means for obscuring the displayed indicator until after the operation of said operating device.

In testimony whereof I affix my signature.
WILLIAM H. ROBERTSON.
